(57) CLAIM

I claim the ornamental design for a flashlight for a pet collar, as shown and described.

DESCRIPTION

FIG. 1 is a perspective view of a flashlight for a pet collar connected to a pet collar;

FIG. 2 is a front perspective view of a flashlight for a pet collar with a light housing in a first position;

FIG. 3 is a rear perspective view thereof;

FIG. 4 is a first side view thereof;

FIG. 5 is a second side view thereof;

FIG. 6 is a top view thereof;

FIG. 7 is a bottom view thereof;

FIG. 8 is a front view thereof;

FIG. 9 is a rear view thereof;

FIG. 10 is a front perspective view of a flashlight for a pet collar with a light housing in a second position;

FIG. 11 is a rear perspective view thereof;

FIG. 12 is a front view thereof;

FIG. 13 is a rear view thereof;

FIG. 14 is a top view thereof;

FIG. 15 is a bottom view thereof;

FIG. 16 is a first side view thereof; and,

FIG. 17 is a second side view thereof.

The broken line showing of the pet collar in FIG. 1 is for environmental purposes only and forms no part of the claimed design. All other broken lines represent unclaimed portions of the article and form no part of the claimed design.
